UNITED STATES PATENT OFFICE.

JOSIAH PEEPER, OF COEUR D'ALENE, IDAHO.

LAWN-SPRINKLER.

1,226,003.

Specification of Letters Patent. Patented May 15, 1917.

Application filed October 9, 1916. Serial No. 124,595.

To all whom it may concern:

Be it known that I, JOSIAH PEEPER, a citizen of the United States, residing at Coeur d'Alene, in the county of Kootenai and 5 State of Idaho, have invented certain new and useful Improvements in Lawn-Sprinklers, of which the following is a specification.

My invention relates to improvements in 10 lawn sprinklers, and the object of my invention is the provision of a portable sprinkler especially designed for the purpose of watering comparatively small strips or areas of grass, such as parking strips and 15 narrow confined spaces.

With the average device of this character there is apt to be considerable wastage of water due to the lack of any means for properly directing the throw of the jets or 20 streams issuing from the sprinkler, as in the case of small plots of lawn where a large percentage of the water generally falls upon the adjoining pavements and is entirely wasted.

25 It is the purpose of my invention to provide a novel construction by means of which the foregoing disadvantage is overcome, and to this end my device includes means whereby the jets or streams of water may 30 be discharged in either of two opposite directions from the sprinkler or, simultaneously in both directions, as may be desired. And further, I provide means whereby the water is projected in such a manner that the 35 watered area will be uniformly irrigated.

Generally speaking, my invention comprises a device having a perforated top or sprinkler head of semi-circular or arcuate form in cross-section, a centrally disposed 40 interior dividing wall extending from end to end thereof which serves to divide the sprinkler body into two separate sprinkler compartments or chambers, and a valve adapted to direct the water from the supply 45 hose or duct to either chamber selectively, or to both chambers simultaneously.

In addition to these principal elements, I also provide means for directing the water through the sprinkler in a single continuous 50 stream, an advantageous and novel arrangement and adaptation of the sprinkler perforations, and supporting elements for the sprinkler body.

The several features of construction, combination and arrangement of parts will be hereinafter fully pointed out, described and

claimed, recourse being had to the accompanying drawings, in which—

Figure 1 is an exterior side view of the 60 complete device.

Fig. 2 is a longitudinal sectional view thereof.

Fig. 3 is a cross-section through Fig. 2 at the valve end of the sprinkler.

Fig. 4 is a cross-section through the 65 sprinkler body.

Referring more specifically to the drawings in which like reference characters are used to indicate like parts in the several views, the numeral 1 designates the perforated dome-like sprinkler head, and 2 the flat bottom portion of the body, said head being provided with a plurality of longitudinal superposed rows of sprinkler perforations 3 extending from end to end of 70 the sprinkler head.

By reference to Fig. 4, it will be observed that the body of the device is divided by the interior vertical longitudinal wall structure 4 into separate chambers 5—5, said 80 wall structure extending from its valve end to the opposite end of the body, and from its top or head portion to the bottom thereof.

Disposed at one end and set in the wall 85 of the perforated sprinkler head portion 1 is the valve 6 having its seat 7 provided with the intake opening 8 and the delivery 90 openings 9—9, and also the extended nozzle passage 10 which is formed by the wall 90 structure 4. The rotatable valve plug 11 has suitably positioned openings 12—12 and 13 which are adapted to register with the former seat openings 9—9 and 10, respectively, when the valve is turned.

95 From the views, Figs. 2 and 3, it is evident that by proper rotation of the valve plug 11, water from the intake opening 8 may be directed to both chambers 5—5 at the same time or to either, selectively, or that the entire supply may be diverted from the chambers and directed and discharged through the nozzle passage 10 out through the nozzle 10', in a single stream.

100 It is desired to here call particular attention to a distinct advantage derived from the arrangement of the sprinkler perforations in connection with the dome-shaped sprinkler head. The perforations of a given row are intended to be bored at a predetermined angle through the wall of the head, 110 say at right angles to the arc of the wall,

This will serve to direct the jets of water from the lowermost row of perforations to a point near the sprinkler, while each succeeding superposed row will project their respective jets at a somewhat greater distance so as not to interfere with the row next below. Hence, confused intermingling of the streams will be obviated and the tendency be to provide a uniform even supply over the watered area.

A handle 14 is provided for the valve, while the pointed shouldered supporting legs 15 at the forward end serve to anchor the sprinkler in the ground, prevent back-lash due to the pressure in the flexible supply hose, and also provide means for elevating or depressing the nozzle 10', so that the stream therefrom may be directed as desired. A coupling 16 is disposed as shown, for convenient attachment of the supply hose.

While I have illustrated and described a practical and preferred form of sprinkler, it is to be understood that I may employ

the principles involved in the construction thereof in more or less modified forms, and yet remain within the scope and spirit of my invention as defined in the appended claim.

Having described my invention, I claim:

A lawn sprinkler having a chambered body, a hollow partition extending longitudinally of the body and dividing it into two separate chambers, one wall of each chamber being perforated, a nozzle connected to the outer end of the hollow partition, a separate intake opening for each chamber and for the hollow partition, a supply duct, a valve adapted to direct liquid from the supply duct selectively to either chamber or to both chambers simultaneously, or to shut it off from the chambers and direct it to the interior of the partition or to cut off the supply entirely.

In testimony whereof, I hereby affix my signature.

JOSIAH PEEPER.
